UNITED STATES PATENT OFFICE.

CARL O. NORDENSSON, OF CHICAGO, ILLINOIS.

OIL-GAS PRODUCER.

1,218,575.

Specification of Letters Patent.

Patented Mar. 6, 1917.

Application filed January 2, 1913. Serial No. 739,646.

To all whom it may concern:

Be it known that I, CARL O. NORDENSSON, a citizen of the United States, and a resident of Chicago, in the county of Cook and State 5 of Illinois, have invented certain new and useful Improvements in Oil-Gas Producers; and I do hereby declare that the following is a full, clear, and exact description thereof, reference being had to the accompanying 10 drawings, and to the characters of reference marked thereon, which form a part of this specification.

This invention relates to improvements in oil gas producers of that kind wherein hydro-carbon oil, such as crude oil, kerosene and the like, is subjected to partial combustion in the presence of a suitable quantity of air or water vapor or steam or both to produce a combustible gas which may be used 20 for various purposes as, for instance, for heating purposes or as a fuel for explosive engines, etc.

Among the objects of the invention is to provide a very simple, compact and efficient 25 producer for this purpose, and the invention consists in the matters hereinafter set forth and more particularly pointed out in the appended claims.

In the drawings:—
80 Figure 1 is a side view of a producer embodying the improvements constituting my invention.

Fig. 2 is a top plan view thereof.
85 Fig. 3 is a vertical section, with parts shown in elevation.

Fig. 4 is a horizontal section taken on the line 4—4 of Fig. 1.

Fig. 5 is detail section on the line 5—5 of Fig. 1.

40 Fig. 6 is a sectional detail showing means to supply air from the preheating chamber to the combustion chamber to support combustion for preliminarily heating the latter.

The producer embraces in its construction 45 a combustion chamber surrounded by a wall of suitable refractory material, as standard fire brick. It comprises a bottom wall 10 and an upright wall 11, herein shown as made circular. It is supported on standards 50 or columns 12, 12, and is closed at its top by a structure embracing a vaporizer chamber 13, the side or upright wall 14 of which is provided with flanged members 15 which, together with the top plate 16 extend outwardly beyond the side wall and overlap the

upright wall 11. The vaporizer chamber is thus conveniently supported and provides one of the bounding walls of the combustion chamber 17. The top plate 16 is provided with a hand hole closed by a cover plate 18. 60

Surrounding said combustion chamber are two independent annular chambers 20, 21 which are formed between three annular sheet metal walls or shells 22, 23, 24 which surround the said chamber and constitute 65 jackets therefor. The said chambers are closed at the upper ends by an annular top plate 25, which supports the vaporizer. The inner chamber 20 is closed at its lower end by a plate 26 which extends entirely across the bottom of the chamber, as shown in Fig. 3. The outer chamber 21 is closed by a similar plate 27, which, however, is spaced from the plate 26 to provide a space or passage 28 which connects the vertical portions of the 70 chamber 21, the whole constituting an exit passage for the products of combustion which are generated in the combustion chamber 17; the said combustion chamber communicating with the exit passage (28, 21) 75 through the opening 31 at the bottom thereof. The products of combustion are finally discharged through a vent or smoke pipe 32 which communicates with the annular portion of the passage at a point remote from the opening 31. In order to prevent the 80 products of combustion from passing directly to the vent pipe the lower or bottom part of the exit passage is closed by a barrier plate 33 arranged between the opening 31 and the vent pipe, and baffle plates 34 are arranged in the vertical part of the exit passage, as shown in Figs. 3 and 4, so as to divert the products of combustion throughout 85 all parts of the exit passage thus formed. The inner annular chamber 20 constitutes a preheating chamber for the air that is to be mixed with the oil prior to the delivery of the oil and air to the generator coil or chamber, the said chamber receiving heat from 100 both its inner and outer sides by the heat of combustion in the chamber 17 and the heat of the products of combustion in the outer or surrounding exit passage 21.

Air under pressure is delivered to the preheating chamber 20 through the pipe 36 and fills all parts of the chamber and its temperature is therein raised. The preheated air is taken from said chamber at the opposite side of the structure and at the top thereof 105

through a pipe 37 that discharges the air into the vaporizer chamber 13. The air in passing through the vaporizer chamber in contact with the heated water therein takes up a percentage of vapor due to the heat and pressure under which the device is operated. The commingled air and vapor is discharged from said vaporizer chamber through the pipe 38 which leads to a suitable injector device, indicated as a whole by 39, where the mixture is admixed with oil furnished thereto in a manner now to be described.

Oil under suitable pressure is supplied to the producer through a pipe 42 which leads into a coil 43 that is submerged in water in the vaporizer chamber 13. The oil is pre-heated in its passage through said coil to facilitate its admixture with the commingled air and vapor at the injector device 39 prior to the admission of the mixture into the generator 45, which, as herein shown, has the form of a coil located in the combustion chamber 17. The oil is led from the pre-heating coil 43 through a pipe 46 to the injector device 39. The said injector device may be of any well known or preferred type. As herein shown, it comprises a pipe 47 which extends through a suitable stuffing box 48 formed in a cast metal plate 49 bolted to the outer shell 24 and through said shell, the shell 23, the plate 50 between the shells 22, 23, and through the shell 22 and the upright wall 11, and is connected at its inner end to the receiving end of the generator coil 45. The said pipe 47 is offset at its outer end to receive a smaller oil pipe 52 that extends a distance into the larger pipe 47. The air pipe 38 and the oil pipe 46 are connected to the pipes 47 and 52, respectively, and are provided with suitable valves 53, 54 to regulate the proportion of the mixture of the gas making constituents. The stems of the said valves may be geared together, as by the gears 55, 56, whereby both valves may be simultaneously adjusted, as by means of the lever arm 57, to thereby maintain a predetermined or fixed proportion of the gas making constituents while providing means for varying the supply of a predetermined mixture to the generator coil.

The gas produced in the generator coil is carried away therefrom by the exit pipe 60 which may lead to any suitable point for the disposal of the gas, as to a storage tank if the gas is to be stored, or to a point for immediate consumption of gas. The gas may pass from the pipe 60 to its point of use, through a scrubber and a purifier, in a well known manner. In order to adjust the supply of gas making constituents to the demands upon the gas I may provide the following regulating mechanism: Connected to the gas outlet pipe 60 is a pipe 61 which discharges at its upper end into a holder 62, the

bell 63 of which dips into a body of water in the holder to seal the same. Said bell is connected, as by means of the counterbalanced cable 64, trained about pulleys 65, with the adjusting arm 57 of the injector device 39 to provide means for automatically regulating the supply of the gas making constituents to the gas generator coil to correspond with the demand upon the resultant gas.

The combustion chamber 17 is provided at one side thereof with an opening which, as herein shown, is formed in two short sections of pipe 65, 66 arranged end to end and extending through the metal plates 49 and 50. The pipe section 65 is inserted outwardly through an opening in the wall 11 and extends into and has screw-threaded engagement with the intermediate plate 50. The pipe section 66 is fitted into an opening in the neck 67 of the outer plate 49 and extends inwardly into and has screw-threaded engagement with the said opening in the plate 50. This arrangement constitutes a simple, convenient and economical mode of forming an opening through the wall of the producer. The said opening is closed at its outer end by a cover plate or door 68 which is hinged at one side at 70 to the outer plate 49 to swing upwardly away from the opening, and is provided at the opposite side with a hook to engage over a stud 71 fitted in the said plate 49.

The said opening thus formed is provided for introducing into the combustion chamber fuel for preliminarily heating the walls of the combustion chamber and the generator coil to a temperature required to generate gas in the coil upon the delivery of the fuel constituents to the coil. This preliminary heating may be effected by means of a burner or torch 73 of any suitable construction which may be supported in any suitable manner, not herein shown, in position to direct the fuel constituents therefrom through the side opening or passage of the producer to the combustion chamber 17 when the cover plate or door 68 is raised into its open position. After the walls of the combustion chamber and the generator coil have been raised to the required temperature the valves of the injector 39 are opened to admit the oil and mixture of air and vapor into the generator coil, where it is acted upon, not only by the exteriorly impressed heat but also by the heat due to partial combustion of the gas making constituents to convert the same into a fixed combustible gas.

When using certain grades of oil as the hydro-carbon constituent of the gas, the partial combustion of the oil within the generator coil may be sufficient to maintain the heat required to convert the constituents into gas. For other grades of oil, it is necessary to maintain a supplemental combustion

within the combustion chamber 17. The fuel to support such supplemental combustion may be taken from any suitable source as, for instance, gas may be taken from the exit pipe 60 and the air to support combustion 5 may be taken from the preheating chamber, when heated air alone is desired, or may be taken from the air and vapor pipe 38 when vapor steam is to be admitted to the combustion chamber. As herein shown, an auxiliary pipe 75 leads upwardly from the gas exit pipe 60 and is directed through suitable openings in the plates 49, 50 and the wall of the combustion chamber to deliver gas 10 to the chamber 17. An auxiliary air pipe 77 may be led downwardly from the air and vapor pipe 38 and, as shown in Figs. 1, 2 and 4, extends through an opening in the neck 67 of the outer plate 49 and inwardly 15 through the side opening formed in the pipe sections 65, 66, with its inner end closely adjacent to the discharge end of the auxiliary gas supply pipe 75. Said auxiliary gas and air pipes 75 and 77 are provided 20 with suitable regulating valves 79, 80 respectively, to regulate the flow of the fuel constituents therethrough so as to produce the proper burning mixture within the combustion chamber 17. In Fig. 6 is shown an air pipe 77' to supply air for supporting combustion, said pipe leading directly from the preheating chamber 20. If desired, however, the fuel constituents to maintain such supplemental combustion may be taken from 25 sources exterior to the producer, but it is advantageous to employ for this purpose heated fuel constituents.

The generator coil, herein shown, comprises a plurality of superposed banks of 30 reverse turns supported in any suitable manner on the walls of the report and connected from end to end of the coil to constitute a continuous zigzag conduit or passage for the flow of the gas making constituents 35 therethrough. The diameters of the turns are increased from the intake end to the outlet end of the coil to correspond with the expansion of the gas making constituents and resultant gas as the same flows through the 40 coil. This construction of the coil provides means for subjecting the gas making constituents to a maximum area of heating surface.

The turns of the coil are so arranged as 45 to subject the gas making constituents to alternate compression and expansion during their passage through the coil so as to thereby result in a complete admixture of the gas making constituents to bring all parts thereof in contact with the heated walls of the coil and prevent the formation of relatively cool cores of the material in the coil such as would tend to occur if no obstruction to the flow of the material therethrough were provided. This result is herein shown as ef-

fected by making the alternate turns of each bank of turns of the coil of different diameters so that the material passes from a turn of one diameter into a turn of a smaller diameter, and from the latter turn into a turn of larger diameter, and so on throughout its course through the coil. The use of alternate turns of different diameters enables the coil to be economically and readily constructed and assembled, it being only necessary to provide reducer return bends for connecting the ends of the turns, while the turns themselves may be made of standard or commercial piping. It will be understood, however, other means of producing 75 this effect may be employed without departing from the spirit of the invention.

Water is supplied from the vaporizer tank through a pipe 83 arranged exterior to the producer shell, with the delivery terminal 85 34 thereof extending upwardly through the combustion chamber 17 and into the bottom of the vaporizer chamber, whereby the water is preliminarily heated before reaching the vaporizer chamber. Any suitable form of 90 overflow device 86 may be applied to the receiving end of the supply pipe 83 to maintain the proper level of water in the said tank or chamber.

The operation of the producer thus described will be apparent from the foregoing, but may be briefly recapitulated as follows:

Air is delivered through the pipe 36 and oil is delivered through the pipe 42 under predetermined pressures from suitable 100 sources of supply. Air in passing through the preheating chamber 20 absorbs some of the heat given off by radiation from the combustion chamber, and from the products of combustion which escape through the 105 chamber or passage 21. The preheated air upon entering the vaporizer chamber takes up a percentage of water, due to the pressure of the air and the temperature of same. The oil in passing through the preheating 110 coil 43 is raised in temperature by heat from the water surrounding the coil. The preheated oil and mixture of air and vapor are intermingled at the nozzle of the injector 39 and are forced under their pressures into 115 the generator coil, which coil and the walls of the combustion chamber have been previously heated by the burner 73. In the passage of the gas making constituents through the coil the partial combustion 120 thereof, in the presence of a limited body of air, converts the constituents into a resultant fixed combustible gas which is led off through the exit pipe 60 to the point of use of the gas. Supplemental combustion is 125 effected and maintained in the combustion chamber 17, if required, by gas and air delivered through the pipes 75 and 77. The products of this supplemental combustion, as well as the preliminary combustion of 130

the burner 73, pass off through the annular space or passage 21 surrounding the pre-heating chamber and out through the vent pipe 32. By reason of the coaction of the air and oil valves of the injector, the volume of the gas making constituents supplied to the generator coil may be varied as desired without increasing or decreasing the richness of the mixture. The proportions of the gas making constituents may, however, be relatively varied if the setting of the interacting gears 55 and 56 be changed.

An advantage of the construction, aside from those hereinbefore enumerated, is found in its compactness. Another advantage is that practically all the material used in the construction of the producer is standard material of commerce. For instance, the walls of the combustion chamber may be made of standard fire brick and the sheet plates and pipes used are standard articles of commercial size.

I am aware that certain of the details of construction may be varied within the scope and spirit of the invention, and the invention is not limited to such details except as hereinafter made the subject of specific claims, or as imposed by the prior art. I have herein referred to a "vaporizer" and to mixing vapor with the preheated air prior to the delivery thereof to the generator. It is to be understood, however, that the term "vapor" has not been used in restrictive sense, but is intended also to include steam when the temperature in the vaporizer is such as to produce steam.

I claim as my invention:

1. An oil gas producer comprising a combustion chamber, a generator coil therein and its exit pipe, an injector discharging into said coil, a vaporizer, an oil supply pipe extending therethrough and discharging into the injector, an air supply pipe leading to said injector through said vaporizer for delivering heated air to the vaporizer and moistened heated air to said injector and means controlled by heat derived from the combustion chamber for supplying heat to the vaporizer.

2. In an oil gas producer, the combination with a generator, and its exit pipe, of means for supplying a preheated mixture of air and vapor to the generator and means controlled by the heat of the vapor producing medium for supplying preheated oil to the generator and for mixing it with the mixture of air and vapor.

3. An oil gas producer comprising a combustion chamber, a generator therein and its exit pipe, a vaporizer heated from said combustion chamber and having means to supply water thereto, means for passing preheated air through the vaporizer and for supplying the air mixed with vapor to the generator, means for supplying oil to the

generator and mixing it with air and vapor, and means for preheating the oil by its passage through the vaporizer.

4. An oil gas producer comprising a closed combustion chamber of refractory material, a generator therein and its exit pipe, an injector discharging into said generator, a vaporizer having means to supply water thereto, an air supply passage leading to the vaporizer with means for preheating the air therein prior to its admission to said vaporizer, and an oil supply pipe leading to said injector, having a portion thereof submerged in the water in said vaporizer whereby the oil is preheated, and an air and vapor pipe leading from said vaporizer to said injector.

5. An oil gas producer comprising a closed combustion chamber of refractory material, a generator therein and its exit pipe, an injector discharging into said generator, a vaporizer having means to supply water thereto, an air supply passage leading to the vaporizer with means for preheating the air therein prior to its admission to said vaporizer, an oil supply pipe leading to said injector, having a portion thereof submerged in the water of the vaporizer whereby the oil is preheated, an air and vapor pipe leading from said vaporizer to said injector and means for maintaining supplemental combustion in said chamber comprising an auxiliary pipe leading from the generator exit pipe to the interior of said chamber, and a pipe for delivering air to said chamber.

6. An oil gas producer comprising a combustion chamber having an exit passage for the products of combustion and open at its top, a vaporizer supported on said chamber walls and closing its open top, with means for supplying water to the vaporizer, a generator within said chamber provided with an exit pipe, means for passing preheated air to the vaporizer and for supplying air mixed with vapor to the generator, means for supplying oil to the generator and mixing it with the air and vapor, and means for preheating the oil by heat derived from the water in the vaporizer.

7. An oil gas producer comprising a combustion chamber having an exit passage for the products of combustion and open at its top, a vaporizer supported on said chamber walls and closing its open top, with means for supplying water to the vaporizer, a generator within said chamber provided with an exit pipe, a preheating chamber for air surrounding the chamber and provided with an air inlet passage, a pipe leading from said preheating chamber to the vaporizer, a pipe leading from said vaporizer to the generator, and an oil supply pipe leading also to said generator and having a portion thereof submerged in the water in said vaporizer.

8. An oil gas producer comprising a com-

bustion chamber of refractory material, two independent chambers surrounding the same and one chamber surrounding the other chamber, the latter or outer chamber having communication with the interior of the combustion chamber and constituting an outlet passage for the products of combustion and having an outlet or vent pipe, and the inner chamber constituting an air preheating chamber and having an air inlet passage, a generator within the combustion chamber, having an exit pipe, means to supply preheated air from the preheating chamber to the generator, and means to supply oil and vapor to the generator and to mix it with the preheated air.

9. An oil gas producer comprising a combustion chamber of refractory material, two independent chambers surrounding the combustion chamber and one chamber surrounding the other chamber, the latter or outer chamber having communication with the interior of the combustion chamber and constituting an outlet passage for the products of combustion and having an outlet or vent pipe, and the inner chamber constituting an air preheating chamber and having an air inlet passage, a generator within the combustion chamber, having an exit pipe, and means for commingling vapor and air with the preheated air.

10. An oil gas producer comprising a combustion chamber of refractory material, two independent chambers surrounding the combustion chamber and one chamber surrounding the other chamber, the latter or outer chamber having communication with the combustion chamber and constituting an outlet passage for the products of combustion and having an outlet or vent pipe and the inner chamber constituting an air preheating chamber and having an air inlet passage, a generator within the combustion chamber, having an exit passage, a vaporizer having means to supply water thereto, communications between said preheating chamber and the vaporizer, a pipe leading from the vaporizer to the generator, and an oil supply pipe leading to the generator and having a portion that is submerged in the water in the vaporizer.

11. An oil gas producer comprising a combustion chamber, two independent chambers surrounding the combustion chamber and one surrounding the other chamber, and having a lower portion which extends beneath the bottom of the combustion chamber, an outlet passage communicating with the bottom portion of the outer chamber, a vent pipe leading from said outer chamber

ber, said inner chamber constituting an air preheating chamber and having an air inlet passage, a generator within the combustion chamber having an exit pipe, a vaporizer, with means for supplying water thereto, means for conducting air from the preheating chamber through the vaporizer to the generator, and an oil pipe leading to the generator with a portion thereof submerged in the water of the said vaporizer.

12. An oil gas producer comprising a combustion chamber, two independent chambers surrounding the same and one chamber surrounding the other chamber, and having a lower portion which extends beneath the bottom of the combustion chamber, an outlet passage communicating with the bottom portion of the outer chamber at one side of the combustion chamber, a vent pipe leading from said outer chamber at the other side of the combustion chamber, baffling means within the outer chamber between the combustion chamber outlet passage and the vent pipe, said inner chamber constituting an air preheating chamber and having an air inlet passage, a generator within the combustion chamber having an exit pipe, a vaporizer, with means for supplying water thereto, means for conducting air from the preheating chamber through the vaporizer to the generator, and an oil pipe leading to the generator with a portion thereof submerged in the water in said vaporizer.

13. An oil gas producer comprising a combustion chamber, a generator coil therein comprising a continuous zigzag conduit of enlarging diameter from its inlet to its outlet, an outlet pipe leading therefrom, said coil being internally constructed to alternately contract and expand fluid passing therethrough, a vaporizer heated by heat derived from the combustion chamber, means for preheating air from the source of heat in said combustion chamber and passing it through the vaporizer, means for conducting preheated, vaporized air from the vaporizer to the generator coil and means for conducting oil to said generator coil embracing means to raise the temperature of the oil by heat derived from the vaporization of liquid in the vaporizer.

In testimony, that I claim the foregoing as my invention I affix my signature in the presence of two witnesses, this 28th day of December, A. D. 1912.

CARL O. NORDENSSON.
